HEEL FOR SHOE OR SIMILAR ARTICLE

Jules Fern, Los Angeles, Calif., assignor to Fern Shoe Company, Los Angeles, Calif., a corporation of California

Filed Sept. 6, 1960, Ser. No. 62,030

Term of patent 3½ years

(Cl. D7—5)

FIG. 1.

FIG. 2.

FIG. 4.

FIGURE 1 is a side elevational view of a heel for a shoe showing my new design, the side opposite thereto being substantially similar in appearance, a shoe being shown in phantom lines illustrating the heel in use;

FIG. 2 is a bottom view thereof;

FIG. 3 is a rear end view thereof; and

FIG. 4 is a sectional view, taken along a plane corresponding to line 4—4 of FIG. 1.

I claim:

The ornamental design for heel for a shoe or similar article, substantially as shown and described.
